UNITED STATES PATENT OFFICE

120,393

DESIGN FOR A CURB SERVICE BATTERY TRUCK

Leon A. Doughty, Glenside, Pa., assignor to
Carlile & Doughty, Inc., a corporation of Pennsylvania

Application September 15, 1939, Serial No. 87,238

Term of patent 3½ years

To all whom it may concern:

Be it known that I, Leon A. Doughty, a citizen of the United States, residing at Glenside, in the county of Montgomery and State of Pennsylvania, have invented a new, original, and ornamental Design for Curb Service Battery Truck, of which the following is a specification, reference being had to the accompanying drawing, forming part thereof.

Figure 1 is a front elevation of a curb service battery truck showing my new design;

Figure 2 is a side elevation of Figure 1; and
Figure 3 is a plan view, broken away slightly at one spot, to show certain details more clearly.

I claim:

The ornamental design for a curb service battery truck, as shown.

LEON A. DOUGHTY.
